Attn:

UNITED STATES PATENT OFFICE

BLAND B. BUTTON, OF CHICAGO, ILLINOIS

COLLAPSIBLE GARMENT HANGER

Application filed March 19, 1931. Serial No. 523,679.

This invention relates to improvements in the construction of collapsible garment hangers, and one of the objects is to provide a hanger which is particularly adapted for use in connection with garments such as women's dresses and the like, to which the hanger is applied through the neck opening rather than from either the front or the back, as in the case of an ordinary buttoned garment.

Another object of the invention is to provide a collapsible hanger having arms which are movable from folded position into self-locking extended position.

The invention will be fully understood from the following detailed description taken in connection with the accompanying drawing, wherein I have shown the preferred form of construction.

Referring to the drawing:

Fig. 1 is a view of the hanger in the extended position, a portion of one of the stretcher arms being broken away to show the slot or channel for receiving the bracing link;

Fig. 2 is a bottom plan view of the hanger in the extended position;

Fig. 3 is a view of the hanger in the collapsed or folded position; and

Fig. 4 is a section through the folded hanger taken on line 4—4 of Fig. 3.

In the embodiment shown the hanger comprises: a vertically disposed bar 5, provided at its upper end with a hook 6 for engaging a hanger support; a pair of stretcher arms 7 and 8 for receiving and supporting the garment; coupling means comprising a pair of links 9 and 11 extending between the inner ends of arms 7 and 8 to provide pivotal and sliding connection between said arms and bar 5; and a pair of bracing links 12 and 13 supported at their inner ends on a pivot 14 carried in the lower end of bar 5, the outer ends of said links being pivoted respectively at 15 and 16 to stretcher arms 7 and 8.

The inner ends of the stretcher arms are connected with links 9 and 11 by means of pins 17 which extend through the ends of the arms and the links positioned on either side thereof. Link 9 is provided with a lateral projection or finger piece 18 which may be grasped by the operator to slide the inner

ends of the arms upwardly on bar 5 to reduce the hanger to the folded condition, as shown in Fig. 3, arms 7 and 8 in this position resting immediately adjacent either side of bar 5.

The inner ends of the stretcher arms are cut to provide bevelled faces 19 which, in the folded condition of the hanger, engage the sides of bar 5 to form a self-locking joint which prevents further spreading of the arms. The joint thus formed between the inner ends of the arms and bar 5 serves to brace the arms in their extended position. The weight of the garment on the arms tends to turn or draw the bevelled faces 19 inwardly against the sides of bar 5 to form a wedging lock.

Links 12 and 13 serve to brace the stretcher arms to hold them in extended position under the weight of the garment. In the extended condition of the hanger these links are inclined upwardly from the horizontal at a slight angle, as shown in Fig. 1. When the arms are folded against bar 5 the links pivot inwardly to assume the position shown in Figs. 3 and 4. The stretcher arms are channeled or grooved, as indicated at 21, to provide recesses for partially housing links 12 and 13 when the arms are collapsed. Also, the lower end of bar 5 is provided with a slot 22 which extends a short distance above pivot 14 to accommodate bracing links 12 and 13 when they assume the position shown in Figs. 3 and 4. By placing links 12 and 13 between the sides of arms 7 and 8 and bar 5 I avoid contact between the links and the garment. If the links were placed on the outside of these parts there would be some danger of their catching and tearing the garment.

The stretcher arms are provided with inwardly bulging portions 23 which engage the sides of bar 5 to prevent joints 15 and 16 from coming directly in line with pins 17, the object of this being to assure spreading of links 12 and 13 when a downward pull is applied to piece 18.

The hanger is particularly well adapted to the hanging of dresses. The dress may be laid on a bed or sofa and the hanger in the collapsed condition may be inserted di-

rectly through the neck opening of the dress. The stretcher arms are then spread by holding the upper end of bar 5 and pulling downwardly on finger piece 18. The dress having been laid out on the bed, it may be thus 5 placed on the hanger without having to be further touched by the hands of the operator. If it is desired to hang a dress while the hanger is on a supporting hook, and in the collapsed condition, it is merely necessary to slip the neck opening of the dress 10 over the lower ends of the stretcher arms, and then pull downwardly on finger piece 18, whereupon the arms are moved outwardly to engage the shoulder portions of the dress. In moving to this position the inner 15 ends of the arms engage the sides of bar 5 to form a self-locking joint. The removal of the dress from the hanger is equally convenient. It is merely necessary to push 20 downwardly on the outer ends of arms 7 and 8, whereupon the angle lock formed between the inner ends of the arms and bar 5 releases itself, collapsing the arms, and allowing the dress to fall from the hanger. 25 The foregoing detailed description has been given for clearness of understanding only, and no unnecessary limitations should be understood therefrom, but the appended 30 claims should be construed as broadly as permissible, in view of the prior art.

What I regard as new and desire to secure by Letters Patent is:

1. A garment hanger comprising a bar provided with means for engaging a hanger support, and a pair of collapsible stretcher arms supported on said bar and provided at their inner ends with means affording pivotal and sliding connection with the bar, the inner 35 ends of said arms being shaped to move into abutting engagement with the sides of the bar when the arms are in the extended position.

2. A garment hanger comprising a bar provided with means for engaging a hanger support, and a pair of collapsible stretcher arms supported on said bar and provided at their inner 40 ends with means affording pivotal and sliding connection with the bar, the inner ends of said arms being shaped to provide shoulders for engaging the sides of the bar to limit the outward movement of the arms.

3. A garment hanger comprising a bar provided with means for engaging a hanger support, stretcher arms adapted to fold from a 45 normally extended position into collapsed position adjacent said bar, and coupling means providing pivotal and sliding connection between said arms and the bar, the inner ends of said arms being shaped to provide 50 shoulders for engaging the sides of the bar to limit the outward movement of the arms.

4. A garment hanger comprising a bar provided with means for engaging a hanger support, a bridge piece slideable on said bar, 55 collapsible stretcher arms pivoted at their

inner ends on said bridge piece, said inner ends of the arms being shaped to provide shoulders for engaging the sides of the bar to limit the outward movement of said arms, and bracing links extending between said bar 70 and the stretcher arms.

5. A garment hanger comprising a bar provided with means for engaging a hanger support, collapsible stretcher arms having their inner ends shaped to abut against the sides of the bar when the arms are in the extended position, and means extending between the inner ends of said arms affording pivotal and sliding connection with said bar, said connecting means including a part engageable by the operator to move the arms from folded position to extended position.

6. A garment hanger comprising a bar provided with means for engaging a hanger support, collapsible stretcher arms having their inner ends shaped to abut against the sides of the bar when the arms are in the extended position, means extending between the inner ends of said arms affording pivotal and sliding connection with said bar said connecting means including a part engageable by the operator to move the arms from folded position to extended position and bracing links extending between said bar and the stretcher arms.

7. A garment hanger comprising a bar provided with means for engaging a hanger support, stretcher arms adapted to be folded from a normally extended position to collapsed position adjacent either side of said bar, means extending between the inner ends of said arms affording pivotal and sliding connection with said bar, and means carried by said connecting means and engageable by the operator to move the arms from folded to extended position, the inner ends of said arms being shaped to move into abutting engagement with the sides of the bar when the arms are in the extended position.

8. A garment hanger comprising a bar provided with means for engaging a hanger support, stretcher arms adapted to be folded from a normally extended position to collapsed position adjacent either side of said bar, means extending between the inner ends of said arms affording pivotal and sliding connection with said bar, means carried by said connecting means and engageable by the operator to move the arms from folded to extended position, the inner ends of said arms being shaped to move into abutting engagement with the sides of the bar when the arms are in the extended position, and bracing links pivoted at their inner ends on said 105 bar, the outer ends of said links being connected to the opposite arms of the hanger.

9. A garment hanger comprising a bar provided with means for engaging a hanger support, a bridge piece slideable on said bar 110

collapsible stretcher arms pivoted at their inner ends on said bridge piece, said inner ends of the arms being shaped to move into abutting engagement with the sides of the bar when the arms are in the extended position, and bracing links extending between said bar and the stretcher arms, portions of said arms and the bar being grooved to partially house the links in the collapsed position of the hanger.

In witness whereof, I hereunto subscribe my name to this specification.
